VAULT COVER GRATING

Emil A. Altobello, 555 Preston Ave.,
Meriden, Conn. 06450

Filed Apr. 19, 1971, Ser. No. 135,521

Term of patent 14 years

Int. Cl. D25—02

U.S. Cl. D60—2

FIG. 1

FIG. 2

FIG. 3

FIG. 4

FIG. 5

FIG. 1 is a top plan view of the vault cover grating.
 FIG. 2 is a bottom plan view of the grating shown in FIG. 1.

FIG. 3 is a front elevation view of the grating shown in FIG. 1.

FIG. 4 is an enlarged sectional view of the grating as seen along the sectioning line 4-4 of FIG. 1.

FIG. 5 is an enlarged side elevation view of the grating partially broken away to show the grating along the sectioning line 5-5 in FIG. 1.

I claim:

The ornamental design for a vault cover grating, as shown and described.
